ELECTRIC SWITCH

Stephen S. Grady, Magnolia, N. C.

Application June 30, 1942, Serial No. 449,644

5 Claims. (Cl. 200—114)

This invention relates to electric switches in general and more especially to electric switch devices designed to resist excessive vibrations resulting from explosions and the like. Among the objects of the present invention it is aimed to provide an improved electric switch having an interposer to separate the main contacts of the switch operated by a switch arm associated with a spring-controlled toggle which will positively anchor the interposer either in current establishing or current interrupting position without danger of displacement by excessive vibrations or shocks such as accompany explosions of torpedoes, bombs and the like whereby fully to satisfy the requirements of a reliable electric switch on board a battleship, torpedo boat, submarine chaser or other vessel engaged in or involved in an armed conflict.

It is still another object of the present invention to provide an improved electric switch device including safety fuses and an electric switch having an interposer to separate the contacts of the switch operated by a switch arm associated with a spring-controlled toggle which will positively anchor the interposer either in current establishing or in current interrupting position, making possible the nesting of the fuses and switch elements together so that a maximum compactness is achieved at a minimum cost so essential in warfaring vessels such as submarines where the conservation of space is one of the essential desiderata.

These and other features, capabilities and advantages of the invention will appear from the subjoined detail description of one specific embodiment thereof illustrated in the accompanying drawing in which

Figure 1 is a plan of a panel equipped with a switch device constituting the present invention in current interrupting position.

Fig. 2 is an enlarged section on the line 2—2 of Fig. 1 also in current interrupting position.

Fig. 3 is an enlarged section on the line 3—3 of Fig. 1 showing the device in current establishing position.

Fig. 4 is an enlarged section on the line 4—4 of Fig. 1 showing the device in current interrupting position.

Fig. 5 is an enlarged section on the line 5—5 of Fig. 2 with the cover removed.

Fig. 6 is an enlarged section on the line 6—6 of Fig. 5 with the cover removed.

In the embodiment shown there is provided a panel base or board 1 composed of some suitable insulating material such as hard vulcanized rub-

ber, "Bakelite" or the like. The base 1 preferably has, as shown, a pocket or clearance 2 in the face 3 thereof to one side of the cheek plate 4 composed of insulated material such as "Bakelite," hard vulcanized rubber and the like extending at right angles to the face 3 and secured to the cross bars 5 and 6 secured to the face 3 of the base 1.

The element relied upon to interrupt the current is the interposer 7, consisting of a plate having a beveled front end portion 8 with the plane lower face slidably mounted and riding on the contact bars 9 and 10 when a two-wire switch is contemplated as here shown. In such case the bars 9 and 10 are disposed to either side of the cheek plate 4 and the interposer 7 slides in the clearance between the lower edge of the cheek plate 4 and the upper faces of the bars 9 and 10.

The bars 9 and 10 are secured in place on the base 1 to either side of the cheek plate 4 by the binding posts 11 and 12 respectively extending through the base 1 with the screw heads 13 disposed in recesses in the base 1 and the threaded portions extending outwardly of the face 3 and of the exposed faces of the bars 9 and 10 with nuts 15 and 16 thereon to lock the binding posts 11 and 12 in position. In addition to the posts 11 and 12 there are also provided the connecting posts 17 having the screw heads 18 and 19 engaging the end portions 20 and 21 of the flexible auxiliary conductors 22 and 23 respectively preferably enclosed in the customary insulating material as shown. These connecting posts 17 extend not only through the end portions 20 and 21 but also through the cross bar 6, the contact bars 9 and 10 respectively, clearing the contacts bars 9 and 10, and through the base 1 terminating in recesses in the base 1 to receive the nuts 24 in such recesses.

The conductors 22 and 23 are in turn connected to the ends of the contact plates 25 and 26 respectively. Each of these plates 25 and 26 has a front contact portion 27 parallel to the outer surfaces of the bars 9 and 10 and also has an outwardly inclined portion 28. On the sides of the contact portion 27 there are formed the upwardly extending ledges 29 and 30 with the recesses 31 and 32 respectively therein to receive the cross bar 33 of the spring 34 having the parallel spring arms 35 and 36, the free ends of which are secured to the cross bar 6 just under the connecting pieces 20 and 21, see Figs. 2 and 5. The spring 34 as shown yieldably maintains the plane plate portion 27 either in engagement with the upper sur-

face of the contact bar 9, 10 in circuit establishing position, that shown in Fig. 3, or in engagement with the upper surface of the interposer 7 in circuit interrupting position, that shown in Figs. 2, 4 and 5.

The mechanism for actuating the interposer 7 into circuit establishing or circuit interrupting position will now be described. Pivotedly connected to one side of the cheek plate 4, there is provided the actuating plate 37 of the actuator. This plate 37 in the present instance, includes an enlarged plate portion 38 and an arm 39. The pivot pin 40 for the plate 37 extends through the portion 38 which is also provided with a spring abutment pin 41 which extends through the arcuate slot 42 in the toggle plate 43. The toggle plate 43 has an extended finger 44 which extends through the opening 45 formed in the interposer 7. On the enlarged portion of the plate 43 and extending from the side thereof, there is provided the abutment pin 46 to receive one leg of the hairpin spring 47, the other leg of which is secured at its free end to the abutment pin 41 extending through the arcuate slot 42. There is also provided a stop pin 48 extending from one side of the cheek plate 4 to cooperate with the lower edge 49 of the enlarged portion 38. From the parts so far described it will appear, see Fig. 4, that when the arm 39 is pressed in one direction, the lower edge 49 of the plate 37 will be arrested by the pin 48, the abutment pin 41 being at one end of the slot 42 and to one side of a straight line drawn between the pivot pin 40 and the abutment pin 46 in which case the interposer 7 by virtue of the finger 44 will be maintained in circuit interrupting position, that is to deflect the contact plate 27 upward and spaced from the contact bars 9 and 10 with the interposer 7 interposed between the plates 27 and the bars 9 and 10 as shown in Fig. 4. On the other hand, when the arm 39 is swung into the other direction, see Fig. 3, the lower edge 49 of the plate 37 will again be arrested by the pin 48. In this instance, however, the pin 41 will be disposed at the other end of the arcuate slot 42 with respect to the position shown in Fig. 4, and the pin 41 will now be disposed to the other side of a straight line drawn between the pivot pin 40 and the abutment pin 46 with respect to the position shown in Fig. 4. In this position, in turn, the interposer 7 under the guidance of the finger 44 will have been moved clear of the plates 27 allowing the same under the urge of the springs 34 snugly to engage the bars 9 and 10 in current establishing position, that shown in Fig. 3.

In current establishing position the current from the binding posts 11 and 12 passes through the bars 9 and 10, then through the contact plates 27 to the conductors 22 and 23 respectively and then to and through the fuses 46' and 47' respectively and from the fuses 46' and 47' through the bus bars 48 and 49 respectively to the binding posts 50 and 51. The fuses 46' and 47' are mounted in the usual way by fuse clips, the clips 52 and 53 being secured between the bar 6 and the end pieces 20 and 21 respectively and the clips 54 and 55 secured to the bus bars 48 and 49 respectively. In this way the fuses 46' and 47' are disposed to either side of the switch arm and adjacent to the contacts to form an exceedingly compact device in the interest of conserving space so necessary in the crowded quarters on the crowded instrument board of the average submarine boat and the like.

Furthermore, this compact arrangement also

lends itself to the use of a small cover which (1) will cover not only the fuses but also the contact portions, but (2) will enable the handle of the switch to be exposed and cooperate with the cover to bar or prohibit removal of the cover except when the contact portions are spaced from one another and the circuit is interrupted. To this end, the cover consists essentially of a rectangular container 56 open at one end with a slot 57 to clear the extension 58 of the cheek plate 4 and another slot 59 through which the handle 39 and part of the enlarged plate portion 38 extends, the handle 39 having a pin 60 extending therethrough with its outwardly projecting ends extending beyond the sides of the slot 59, the pin 60 being longer than the width of the slot 59 so that the cover 56 cannot be removed when the handle 39 is in the circuit establishing position, as shown in Fig. 3. However, due to the recesses 61 and 62 communicating with the slot 59 adjacent the end 63 of the slot 59, when the handle 39 is swung toward the end 63 of the slot 59, that shown in Figs. 1 and 4, the projecting ends of the pin 60 will register with the recesses 61 and 62 and permit the cover 56 to be slipped out of the covering position. The cover serves also as a guide for the interposer 7 when in covering position, the side walls 64 and 65 slidably engaging the ends of the interposer 7, the end wall 66 engaging one end of the cheek plate 4 and the outer face of the bar 6, while the other end wall 67 engages the other end of the cheek plate 4.

It is of course obvious that the base 1, cross bars 5 and 6, interposer 7, cheek plate 4 and container 56 will be composed of a suitable insulating material such as "Bakelite," hard vulcanized rubber and the like.

It is obvious that various changes and modifications may be made to the details of construction without departing from the general spirit of the invention as set forth in the appended claims.

I claim:

1. In an electric switch, an incoming conductor, an outgoing conductor, a fixed contact connected to the incoming conductor, a movable contact normally urged into engagement with said fixed contact, a fuse disposed adjacent to said fixed contact, one end of said fuse connected to the outgoing conductor, an auxiliary conductor extending from said movable contact to the other end of said fuse whereby said fixed contact, auxiliary conductor and fuse assume a compact fan-folded relationship to one another, and an interposer slidably mounted on said fixed contact and operable to space said movable contact from said fixed contact into circuit interrupting position.

2. In an electric switch, a base, a fixed contact secured to said base, a fuse connected to said base adjacent to said fixed contact, a movable contact normally urged into engagement with said fixed contact, an incoming conductor connected to one end of said fixed contact, an outgoing conductor connected to one end of said fuse, an auxiliary conductor connecting said movable contact to the other end of said fuse whereby said fixed contact, auxiliary conductor and fuse assume a compact fan-folded relationship to one another, an interposer slidably mounted on said fixed contact and operable to space said movable contact from said fixed contact in circuit interrupting position, a cheek plate mounted on said base to one side of said fixed contact and fuse, a pivotally mounted han-

dle on said cheek plate, and means for operatively connecting said handle to said interposer to control the operation of said interposer.

3. In an electric switch, a base, a fixed contact secured to said base, a fuse connected to said base adjacent to said fixed contact, a movable contact normally urged into engagement with said fixed contact, an incoming conductor connected to one end of said fixed contact, an outgoing conductor connected to one end of said fuse, an insulation covered flexible auxiliary conductor connecting said movable contact to the other end of said fuse whereby said fixed contact, auxiliary conductor and fuse assume a compact fan-folded relationship to one another, an interposer slidably mounted on said fixed contact and operable to space said movable contact from said fixed contact in circuit interrupting position, a cheek plate mounted on said base to one side of said fixed contact and fuse, a pivotally mounted handle on said cheek plate, and toggle means for operatively connecting said handle to said interposer to control the operation of said interposer.

4. In an electric switch, a base, a fixed contact secured to said base, a fuse connected to said base adjacent to said fixed contact, a movable contact, a spring normally urging said movable contact into engagement with said fixed contact, an incoming conductor connected to one end of said fixed contact, an outgoing conductor connected to one end of said fuse, an auxiliary con-

ductor connecting said movable contact to the other end of said fuse whereby said fixed contact, auxiliary conductor and fuse assume a compact fan-folded relationship to one another, an interposer slidably mounted on said fixed contact and operable to space said movable contact from said fixed contact in circuit interrupting position, a cheek plate mounted on said base to one side of said fixed contact and fuse, a pivotally mounted handle on said cheek plate, and toggle means for operatively connecting said handle to said interposer to control the operation of said interposer.

5. In an electric switch, a base, a pair of contact bars fixed to said base, a pair of fuses connected to said base and parallel to and adjacent to said bars respectively, a pair of movable contacts, one for each of said fixed contacts, a spring for each movable contact normally urging it into engagement with one of said fixed contacts, a pair of incoming conductors connected to one of the ends of said fixed contacts respectively, a pair of outgoing conductors connected to one of the ends of said fuses respectively, a pair of flexible auxiliary conductors each connecting one of said movable contacts to the other end of one of said fuses whereby said fixed contacts, auxiliary conductors and fuses assume compact fan-folding relationships to one another, an interposer slidably mounted on said fixed contacts and operable to space both of said movable contacts from said fixed contacts in circuit interrupting position, a cheek plate mounted on said base with a fixed contact auxiliary conductor and fuse to each side of it, a pivotally mounted handle on said cheek plate, and toggle means for operatively connecting said handle to said interposer.

STEPHEN S. GRADY.
